R. S. REID

SASH FASTENER

Filed Sept. 29, 1913

Patented Nov. 3, 1925.

1,560,429

UNITED STATES PATENT OFFICE.

ROBERT STUART REID, OF PRINCE ALBERT, SASKATCHEWAN, CANADA.

SASH FASTENER.

Application filed September 29, 1913. Serial No. 792,476.

To all whom it may concern:

Be it known that I, ROBERT STUART REID, a subject of the King of Great Britain, residing in the city of Prince Albert, in the Province 5 of Saskatchewan, Canada, have invented certain new and useful Improvements in Sash Fasteners, of which the following is the specification.

The invention relates to improvements in 10 sash fasteners and an object of the invention is to provide a fastener which upon the lower sash being independently locked closed will act to positively lock the upper sash against opening and which is also 15 designed such that should the upper sash be opened for ventilating or such like purposes and the lower sash subsequently locked closed it is impossible for one to open the top sash any further, although the same 20 will close freely.

A further object is to construct the fastener such that upon the bottom sash being unlocked and raised the top sash is free to operate either up or down.

25 A still further object is to construct the invention in an extremely simple, cheap and durable manner and so that it can be readily applied to existing windows.

With the above more important objects in 30 view the invention consists essentially in the arrangement and construction of parts hereinafter more particularly described and later pointed out in the appended claims, reference being had to the accompanying drawings in which:

Fig. 1 is a side view of a window equipped with my invention.

Fig. 2 is an enlarged detailed horizontal sectional view at 2-2' Fig. 1.

40 Fig. 3 is a vertical sectional view at 3-3' Fig. 2 and looking towards the outer sash.

Fig. 4 is a vertical sectional view at 4-4' Fig. 2 and looking towards the inner sash.

45 Fig. 5 is a perspective view of a portion of the window frame and showing the catch.

Fig. 6 is an enlarged detailed vertical sectional view at 6-6' Fig. 1.

In the drawing like characters of reference indicate corresponding parts in the several figures.

The window frame 1 is of the ordinary type and it is fitted with the customary vertically slidable inner and outer sashes 2 and 3, the sashes operating between the window strip 4, the parting strip 5 and the storm

strip 6, secured to the frame in the ordinary manner. The sashes can be counterbalanced or not, as desired.

In supplying a window with my invention 60 it is necessary that some means be employed for positively locking the inner or lower sash closed when desired.

The lock 7, which I herein show, is located centrally on the bottom member of the lower sash and comprises a facing plate 8 suitably fastened to the sash and provided with a finger hook 9. The facing plate carries a pivoted latch 10 with which a pressure spring 11 is associated, the latch and spring 70 being suitably housed within a cavity 12 provided in the sash.

The latch is positioned such that it will catch a staple 13 driven into the sill of the frame and in so doing will lock the lower 75 sash against opening. The catch is shown as caught on the staple in Figure 6 of the drawing.

In order to positively lock the latch I have 80 fitted it with a screw threaded shank 14 which protrudes through the plate 8 and carries a lock nut 15. Obviously, by tightening up the nut the latch is pulled inwardly and held permanently caught on the staple.

To release the latch one simply unscrews 85 the nut 15 and presses the shank inwardly to free the latch from the staple.

I might here mention that the finger piece 9 overhangs the nut, thereby making it 90 difficult for one, such as a thief, to release the nut by working from above.

Whilst I have entered into a detailed description of this lock I wish it to be understood that I do not desire to be limited to such an appliance as any device which will 95 positively lock the lower sash closed will serve my purpose.

More or less centrally of the height of the frame I recess the same to provide two opposing similar substantially V-shaped 100 pockets 16 and 17, these pockets being located at opposite sides of the parting strip.

Customarily the parting strip is mounted in a vertical channel 18 provided in the frame and the notching is best done by first removing the parting strip and then cutting away the frame to provide the said pockets 16 and 17.

The notches formed are connected by a cross channel or groove 19 and in the pocket 16 I mount a triangular shaped wearing plate 20 fitted at the lower edge with a right 110

angled flange 21. This plate really faces the side and bottom of the pocket and it is held in place by a screw 22 screwed into the frame.

5 The fastener 23 which I supply presents a short dog 24 and a long dog 25 connected by a cross shank 26. The dog 24 has the end thereof curved slightly downwardly, whilst the dog 25 has the end curved slightly upwardly. This fastener is put in place within the pockets, with the shank 26 entered in the groove 19, the dog 24 in the pocket 16 and the dog 25 in the pocket 17. Obviously, the parting strip requires to be moved to 10 insert the fastener and after the parting strip has been replaced the shank 26 is pivotally retained within the groove.

15 This corner of the outer sash adjoining the parting strip is rabbetted and to the said inner corner I secure permanently a vertically extending rack 27 presenting a plurality of ratchet teeth 28 adapted to be engaged by the short dog 24 when the said dog is in its lowermost position and the arrangement of the teeth is such that they prevent the opening of the sash upon engagement with the said dog.

20 The upper inner corner of the inner sash is provided with a pocket 29 which is adapted to receive the dog 25 when the inner sash is closed. The wall of the pocket is, however, arranged such that upon the said inner sash being opened the dog 25 will be raised and such movement will act to simultaneously raise the dog 24 and pass it clear of the ratchet teeth. The lower end of the rack terminates a short distance above the lower end of the outer sash and is best shown in 25 Fig. 3.

40 Accordingly, when the lower sash is opened the dog 24 is held entirely clear of the ratchet teeth, such being due to the fact that the end of the dog 25 is then riding or contacting with the edge of the sash and will 45 not move until such time that the pocket presents itself.

45 In order to better understand the action I will first assume that the lower sash is held closed by the lock 7 and that the pocket 50 29 is positioned such that it receives the dog 25 which is resting in the position as best shown in Fig. 4. If the upper sash be at this time closed it cannot be opened for the reason that the dog 24 to engage with and 55 lock against the underside of the lowermost tooth of the rack. It is to be understood, in this connection that the closed upper sash has a very limited vertical movement which is determined by the distance between the lowermost racktooth and the bottom of the sash.

60 If one desires to have their upper sash open, such as for ventilating purposes, they will first release the lock 7 and open the lower sash; which action will raise the dog 25 and will consequently pass the dog 24

away from the ratchet teeth. In this connection it is to be understood that the dog 25 actually forces the upper sash upwardly a limited amount, such upward movement permitting the door 25 to clear the lowermost tooth. The upper sash can then be opened any required amount. One then closes and locks the lower sash and when this occurs the dog 25 again enters the pocket 29 and permits the dog 24 to engage one of the ratchet teeth. The upper sash cannot then be opened further, although it is free to close.

65 It is pointed out also that should the lower sash be opened one can open and close the upper sash as they desire.

70 This fastener is particularly desirable as it is cheap, durable and effective and can be readily installed and it permits one to positively lock both sashes closed or to have a 75 certain amount of ventilation by the opening of the upper sash and without having to worry about sneak thieves entering a house through the window.

75 What I claim as my invention is:

80 1. In a window, the combination with vertically slidable upper and lower sashes, of a pivoted fastener carried by the frame and presenting a pair of dogs extending towards the sashes, one of said dogs being adapted to enter a pocket provided in the upper corner of the lower sash in the closed position of said sash and a rack bar secured to the side of the upper sash and presenting ratchet teeth engageable with the other of the dogs and locking the upper sash against opening during the interval that the former dog is in the pocket.

85 2. In a window, the combination with vertically slidable upper and lower sashes, of a fastener pivotally carried by the frame and presenting a comparatively short dog extending toward the upper sash and a comparatively long dog extending toward the lower sash, said long dog being received in a pocket provided in the upper corner of the lower sash when the latter is in closed position, and a rack bar permanently secured to the side of the upper sash and presenting ratchet teeth adapted by engagement with the short dog to prevent further opening from a pre-selected position of the upper sash during the interval that the long dog is in the pocket of the lower sash.

90 3. The combination with a window frame, of a fastener pivotally mounted in the side of the frame and substantially midway of the height thereof and presenting a comparatively long dog extending into the sash channel of the inner frame and a relatively shorter dog extending into the sash channel of the outer frame.

95 In testimony whereof I have signed this specification.

100 ROBERT STUART REID.
